UNITED STATES PATENT OFFICE.

ROBERT S. AVERY, OF WASHINGTON, DISTRICT OF COLUMBIA.

DESIGN FOR A FONT OF PHONETIC PRINTING-TYPE.

SPECIFICATION forming part of Design No. 22,613, dated July 18, 1893.

Application filed June 15, 1893. Serial No. 477,751. Term of patent 14 years.

To all whom it may concern:

Be it known that I, ROBERT S. AVERY, a citizen of the United States, residing at Washington city, in the District of Columbia, have invented and produced a new and original Design for a Font of Phonetic Printing-Script, of which the following is a specification, reference being had to the accompanying drawing, showing a part thereof.

My design for phonetic printing script, or types for printing in imitation of hand-writing, is fully illustrated in the accompanying drawing, the upper and lower case letters being arranged in parallel and contiguous rows. It will

be noted that the slope of the several letters 15 from the vertical, to the right, is about thirty degrees. This font of phonetic script is complementary to my font of phonetic printing type for which I have received a design patent dated May 30, 1893. 20

What I claim is—

The design for a font of phonetic, printing script, substantially as shown.

ROBERT S. AVERY.
